UNITED STATES PATENT OFFICE.

THOMAS DUQUETTE, SR., OF NORTH GROSVENOR DALE, CONNECTICUT.

TELEPHONE-MOUTHPIECE WITH ANTISEPTIC ATTACHMENT.

1,083,671.

Specification of Letters Patent.

Patented Jan. 6, 1914.

Application filed September 27, 1913. Serial No. 792,170.

To all whom it may concern:

Be it known that I, THOMAS DUQUETTE, Sr., a citizen of the United States, residing at North Grosvenor Dale, in the county of Windham and State of Connecticut, have invented certain new and useful Improvements in Telephone-Mouthpieces with Antiseptic Attachments, of which the following is a specification, reference being had to the accompanying drawings.

This invention relates to certain improvements in telephone mouth pieces with antiseptic attachments, and the object of the invention is to provide a device of this general character having means of a novel and improved character capable of operation to effectually prevent the ingress of dust or germs to the interior of the mouth piece and thus render the same thoroughly sanitary.

The invention consists in the details of construction and in the combination and arrangement of the several parts whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in elevation with a part broken away of an antiseptic attachment constructed in accordance with my invention in applied position on a telephone mouth piece; Fig. 2 is a view in front elevation of the device as shown in Fig. 1; Fig. 3 is a sectional view taken vertically through the device as shown in Fig. 1; Fig. 4 is a view in detail of the ring member herein disclosed adapted to engage the mouth piece; Fig. 5 is a transverse sectional view taken through Fig. 3; Fig. 6 is a side view of the device shown in Fig. 4; and Fig. 7 is a sectional view of the device as herein set forth with the cap or closure member adjusted into an open position.

As disclosed in the accompanying drawings, 1 denotes a mouth piece of any ordinary or preferred construction provided with a laterally directed annular flange 2 on which is adapted to be sprung the annular member or ring 3 produced from suitable flattened material, preferably metal.

Hingedly connected with the ring 3, as at 4, is the cap member 5 which forms a closure for the mouth piece and is provided with a chamber 6 in which the disinfectant is adapted to be maintained. This cap member 5 when adjusted into closed position is adapted to have its flange 7 overlap the annular member or ring 3 whereby it will be readily observed that the mouth piece is effectually guarded against the ingress of dust or germs when the device is not in use, it being obvious that when the transmitter is to be used the cap is adjusted into an open position.

To maintain the cap 5 in its closed position, I have depending at a predetermined point on the flange 7 of such cap 5 the spring latch 8 having produced therein an opening 9 adapted to accommodate the outwardly directed indentation or projection 10 pressed from the annular member or ring 3 whereby it will be clearly apparent that the cap 5 will be effectually held in its closed adjustment and that such latch will automatically serve to create the proper action to maintain the cap in such closed position.

In applying the disinfectant or germicide, I prefer to employ an absorbent body 11 such as a sponge which is adapted to be inserted within the chamber 6 of the cap 5 and to be maintained therein through the medium of the porous body 12, preferably cloth, which has its marginal portions clamped between the flange 7 of the cap 5 and a second annular member or ring 13, insertible within the cap 5 and adapted to bear tightly against the flange whereby it will be clearly apparent that proper clamping action is created to maintain the porous body or cloth against displacement.

It is to be observed that by having the ring 3 in engagement with the annular flange 2 provided on the mouth piece that the direction in which the cap or closure 5 is adjusted into open position may be varied as required as it is my purpose to have the ring 3 capable of rotary movement about the flange 2.

From the foregoing description of my improvements, it is thought to be obvious that a telephone mouth piece with an antiseptic attachment constructed in accordance with my invention is of an extremely simple and comparatively inexpensive nature and is particularly well adapted for use by reason of the convenience and facility with which the

attachment may be applied to the mouth piece and of the convenience and readiness with which the antiseptic solution may be placed in proper position within the closure member and retained therein and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

- 15 1. A device of the character described including an annular member adapted to be sprung upon the mouth piece of a telephone, a cover hingedly connected with the annular member and provided with an annular flange 20 adapted to overlap such member, such flange affording a chamber in the cap, an absorbent body adapted to be positioned within the chamber, and porous means for maintaining the absorbent body against displacement.
- 20 2. A device of the character described including an annular member adapted to be sprung upon the mouth piece of a telephone, a cover hingedly connected with the annular

member and provided with an annular flange adapted to overlap such member, such flange affording a chamber in the cap, an absorbent body adapted to be positioned within the chamber, a porous body extended across the chamber, and a ring insertible within the flange of the cap and adapted to engage the marginal portions of the porous body for holding such body in operative position.

3. In combination, a telephone mouth piece provided with an annular flange, an annular member adapted to be sprung upon the flange of the mouth piece and capable of movement therearound, a cover hingedly connected with the annular member and provided with an annular flange adapted to overlap such member, such flange affording a chamber in the cap, an absorbent body adapted to be positioned within the chamber, and porous means for maintaining the absorbent body against displacement.

In testimony whereof I hereunto affix my signature in the presence of two witnesses.

THOMAS DUQUETTE, SR.
